UNITED STATES PATENT OFFICE.

FRED MOSS, OF NEW YORK, N. Y., AND RICHARD COOK, OF EAST NEWARK, NEW JERSEY.

COP-TUBE MACHINE.

SPECIFICATION forming part of Letters Patent No. 373,566, dated November 22, 1887.

Application filed July 8, 1887. Serial No. 243,755. (No model.)

To all whom it may concern:

Be it known that we, FRED MOSS and RICHARD COOK, both citizens of Great Britain, and residents, respectively, of New York, in the 5 county and State of New York, and of East Newark, in the county of Hudson and State of New Jersey, have jointly invented new and useful Improvements in Cop-Tube Machines, of which the following, taken in connection 10 with the accompanying drawings, is a specification.

This invention relates to improvements in machines for making spirally-wound paper cop-tubes of the kind used for spinning cop- 15 yarn on mule-spindles, and it is carried out as follows, reference being had to the accompanying drawings, wherein—

Figure 1 represents a plan view of the machine. Fig. 2 represents a front elevation of 20 it. Fig. 3 represents an end view, seen from x in Fig. 2, showing in section the paste-receptacle. Fig. 4 represents a cross-section on the line A B, shown in Fig. 1. Fig. 5 represents a section of the shipper device on the 25 line C D, also shown in Fig. 1. Figs. 7 and 8 represent, in enlarged side view and longitudinal section, the kind of cop-tube that the machine is designed to produce; and Fig. 6 represents a plan of the paper strip from which 30 the cop-tube is made.

Similar letters refer to similar parts wherever they occur on the different parts of the drawings.

a' represent the upright frames of the machine, the lower ends of which are secured in 35 a suitable manner to the base or table-top b, as shown.

c is the driving-shaft, located in bearings in the frames a' and provided with fast and 40 loose pulleys c' c'', by means of which and a strap or belt from a rotary driving-pulley a rotary motion is imparted to said driving-shaft c.

c' is a brake drum or wheel secured to the 45 driving-shaft c, which may be provided with a suitable brake-shoe, if so desired, for stopping the machine when the belt is slipped from the fast to the loose pulley on the driving-shaft; but this is not essential.

On the driving-shaft c is secured the gear- 50 pinion c', the teeth of which mesh in the teeth

of the intermediate pinion, d, located on the shaft d'. The teeth of the intermediate pinion, d, mesh in the teeth of the gear-wheel e, secured to the shaft e', said shaft having secured to it, outside of the frame a, the paste-roller e', that is partially submerged in the paste, E, contained in the paste-trough E, as shown in Fig. 3.

To the driving-shaft c is secured the gear-wheel c', the teeth of which mesh in the teeth of the pinion f', secured to the cop-tube shaft f, that is journaled in bearings in the frames a a', and by this means a quick rotary motion is imparted to said shaft f. The forward end 65 of the shaft f, outside of the frame a, is made slightly tapering, as shown at f'' in Figs. 1 and 2, and upon it is wound the strip of paper F', Fig. 6, for forming the tapering tube F. (Shown in Figs. 7 and 8.)

g is a rock-shaft located in bearings in the frames a a', and it has secured to it the lever g', the outer end of which is pivoted to a link, g'', having its lower end hinged to a vertically-movable post or rod, G. The post G, link g'', 75 and lever g' are normally held in the positions shown in Fig. 4 while the cop-tube is being made by the influence of the spring G', one end of which is connected to the bar G or a projection thereon, and having its other end 80 connected to a standard, G'', secured to the frames a a', as shown. We have shown the spring G' as being coiled; but this is not essential, as any other suitable spring or weight may be used for the purpose of automatically 85 raising the post G without departing from the spirit of our invention.

a' is a stationary bar or projection secured to frames a a', or either of them, and said projection a' serves as a stop to limit the upward 90 motion of the lever g', the link g'', and rod G, as shown in Fig. 4.

To the rock-shaft g is secured the arm or lever h, having loosely journaled on a pin in its upper end the belt-carrying roller h', from 95 which leads to the roller e'' the endless paste-carrying belt or band H, that may be made of rubber or other suitable elastic or inelastic material, as may be desired. During the operation of forming the cop-tube the said endless 100 band H is held taut against the cop-tube spindle f'' by the influence of the spring G' and

the connecting mechanism to the arm h , as above described. When the cop-tube is finished, the rod G is depressed by means of a treadle of any ordinary construction, such 5 treadle being, however, not shown in the drawings, and when such rod G is depressed against the influence of the spring or weight G' the shaft g is rocked, causing the lever h to move in the direction shown by arrow in Fig. 3, thus 10 withdrawing the endless band H from the cop-tube spindle f'' , to permit the finished cop-tube to be thrown off from said spindle f'' .

For the purpose of automatically starting and stopping the machine we employ the following mechanism: To the vertically-adjustable rod G is secured the wedge or cam G^3 , (shown in Fig. 5,) which, as it moves upward with the rod G , forces a shipper-bar, i , to the position as shown in Figs. 1 and 5, and thereby 15 ships the driving-belt onto the fast pulley c' by means of the prongs $i' i'$, secured to said shipper-bar. The shipper-bar i is guided in one end through a perforation in the frame a' and in its other end in a perforation in a post 20 or bearing, b' , secured to base b , or in any other suitable or equivalent manner. When the rod G is forced downward after the cop-tube is finished, the shipper-bar i is automatically moved toward the left in Fig. 5 by the 25 influence of a spring, I , one end of which is secured to the shipper-bar i and the other end secured to the frame a' , or any other stationary part of the machine, causing the prongs $i' i'$ to ship the driving-belt from the fast to 30 the loose pulley c'' and thereby stopping the machine.

In connection with the cop tube spindle f'' we use an automatic device for knocking off the cop-tube, when finished, from said spindle, and this is carried out as follows: In guides 40 in the frames $a a'$ is arranged the bar k , that is normally held in the position shown in Figs. 1 and 2 by the influence of a spring, k' , secured in one end to said bar k or a projection thereon, and in its other end to a post or rod, k'' , secured to the base b ; or, if so desired, any other or equivalent spring or weight may be used for this purpose.

To the forward end of the sliding bar k is set 50 cured or made in one piece the arm or bracket k^3 , the rear end of which is perforated to allow it to slide longitudinally on the cop-tube spindle f'' , that passes through such perforated end of the arm k^3 . It will thus be seen that the 55 cop-tube may be thrown off from the spindle f'' by moving the bar k and its arm k^3 toward the left, as shown in Fig. 1.

k^4 is a guide-pin secured to the throw-off arm k^3 , over which the paper strip is guided 60 to the spindle f'' during the making of the cop-tube.

k^5 is a gage made adjustable on the pin k^4 for the purpose of guiding the paper strip properly to the spindle f'' in starting the 65 making of the cop-tube.

The cop-tube is automatically thrown off the spindle f'' by connecting mechanism from the

rock-shaft g and treadle-bar G when the machine is stopped, as follows: On the rock-shaft g is secured the lever or arm g^3 , (shown in 70 Figs. 1, 2, and 4,) which, when the bar G is depressed, come in contact with the lower leg of the bell-crank lever l , pivoted on the fulcrum-pin l' , and causes the upper leg of such bell-crank lever to actuate a pin or projection, k^6 , 75 secured to the throw-off bar k , and thus to move the latter toward the left against the influence of the spring or weight k' .

k^7 in Fig. 2 is a spring secured to the pin k^6 or the bar k , and having its free end pressing on the upper leg of the bell-crank lever l , for holding the latter in contact with said pin on the bar k as the latter is reciprocated; but this is not essential, as another pin secured to the bar k may serve the same purpose. 80

The operation of our improved machine is as follows: By relieving the downward pressure on the rod G the spring G' raises the lever g^3 to the position shown in Fig. 4 at the same time as the bar k is drawn backward by its spring k' to the position shown in Fig. 1, and the shipper-bar i moved by the cam or incline G^3 to the position shown in Figs. 1 and 5, causing the driver-belt to be shipped on the pulley c' , by which a quick rotary motion is 90 imparted to the cop-tube spindle f'' and a slower rotary motion imparted to the paste-roller e'' , causing the endless belt H to be set in motion and to be held against the cop-tube spindle f'' with a proper pressure during the 100 travel of said endless belt. A proper amount of paste or other suitable adhesive material is thus taken from the paste-trough E to the traveling belt H . A strip of paper, F' , Fig. 105 6, is then taken by the operator, and its forward end, F'' , introduced between the under side of the rotating spindle f'' and the paste-carrying band H , causing the strip to be pasted and wound spirally on said spindle f'' , the operator meanwhile guiding the strip, as 110 shown in dotted lines in Fig. 3—that is, holding it with a proper tension against the guide-rod k^4 and up to the gage k^5 , as shown in dotted lines in Figs. 1 and 3. After the whole length of the paper strip has been wound on 115 the spindle f'' , an internally and externally tapering cop-tube, F , is produced, as shown in enlarged views in Figs. 7 and 8. By depressing the rod G against the influence of its spring G' the cam or incline G^3 is released from 120 the shipper-rod i , and the latter is carried inward by the influence of its spring I sufficiently to ship the driving-belt onto the loose pulley c'' , causing the spindle f'' and the paste-carrying belt and its rollers to stop, the belt 125 H to be withdrawn from contact with the spindle f'' , and the throw-off arm k^3 and its bar k to be moved against the influence of the spring k' toward the left, and thereby causing the piece k^3 to force the finished cop-tube from the spindle f'' , when it may be picked up by 130 the operator and placed on a drying-rack or otherwise disposed of, as may be desired. After one cop-tube has been thrown off from the

spindle f'' , the operator releases the rod G , causing the machine to be again set in operation, a second strip of paper is guided onto the spindle f'' , and so on.

5 Having thus fully described the nature, construction, and operation of our invention, we wish to secure by Letters Patent and claim—

1. In a cop-tube machine, the rotary spindle f'' , and the endless paste-distributing band H and intermediate connecting mechanism, substantially as described, to the driving-shaft e , combined with the automatic belt-shipper device, consisting of the spring-pressed rod G , the cam or incline G' , secured to it, and the shipper-bar i , with its spring I , substantially as and for the purpose set forth.

2. In a cop-tube machine, the rotary cop-tube spindle f'' and endless paste-distributing band H , in combination with the throw-off device for the cop-tube, consisting of the spring-pressed rock-lever g' , the lever l , the spring-pressed throw-off bar k , and its throw-

off piece k'' , all arranged and combined to operate substantially as and for the purpose set forth. 25

3. In a cop-tube machine, the following elements in combination, viz: a rotary cop-tube spindle, an endless paste-distributing band, and means for holding and releasing it from said spindle, an automatic belt shipping 30 device, and a cop-tube throw-off device, all arranged and connected for automatic operation with a single spring-pressed rod, G , substantially as and for the purpose set forth.

In testimony whereof we have signed our 35 names to this specification, in the presence of two subscribing witnesses, on this 2d day of July, A. D. 1887.
